DESIGN FOR A CUFF LINK OR
SIMILAR ARTICLE

Otto Grun, New York, N. Y.

Application March 9, 1946, Serial No. 127,279

Term of patent 14 years

(Cl. D17—7)

To all whom it may concern:

Be it known that I, Otto Grun, a citizen of the United States, residing in the Borough of Manhattan, city, county, and State of New York, have invented a new, original, and ornamental Design for a Cuff Link or Similar Article, of which the following is a specification, reference being had to the accompanying drawing, forming part thereof.

On the drawing,

Fig. 1 is a front elevational view of a cuff link, showing my new design;

Fig. 2 is a plan view thereof; and

Fig. 3 is a rear elevational view of the same.

My design for a cuff link is characterized by the specific configuration of the two ends of the same, such as the concave top and back, and the shape of the openings representing mouths and eyes, all as illustrated on the drawings.

I claim:

The ornamental design for a cuff link or similar article, as shown and described.

OTTO GRUN.
